US00D858435S

(12) **United States Design Patent** (10) **Patent No.:** **US D858,435 S**
(45) **Date of Patent:** **** Sep. 3, 2019**

(54) **CHARGING BASE FOR AN ELECTRIC VEHICLE CHARGING STATION**

(71) Applicants: **Stefan Helnerus**, Arnsberg (DE);
Stefan Hillenmayer, München (DE)

(72) Inventors: **Stefan Helnerus**, Arnsberg (DE);
Stefan Hillenmayer, München (DE)

(73) Assignee: **innogy SE**, Essen (DE)

(**) Term: **15 Years**

(21) Appl. No.: **29/612,763**

(22) Filed: **Aug. 3, 2017**

(30) **Foreign Application Priority Data**

(57) **CLAIM**

The ornamental design for a charging base for an electric
vehicle charging station, as shown and described.

DESCRIPTION

The sole FIGURE is a perspective view of a charging base
for an electric vehicle charging station.

1 Claim, 1 Drawing Sheet
